Primary Examiner — Sheryl Lane*Assistant Examiner* — Aula Soroush(74) *Attorney, Agent, or Firm* — Dunlap Bennett & Ludwig, PLLC; Anna L. Kinney(57) **CLAIM**

The ornamental design for a pet carrier, as shown and described.

DESCRIPTION

FIG. 1 is a top front perspective view of a pet carrier, showing my new design;

FIG. 2 is a top rear perspective view thereof;

FIG. 3 is a front elevation view thereof;

FIG. 4 is a top plan view thereof;

FIG. 5 is a rear elevation view thereof;

FIG. 6 is a bottom plan view thereof;

FIG. 7 is a right-side elevation view thereof;

FIG. 8 is a left-side elevation view thereof; and,

FIG. 9 is a top front perspective view thereof in use with a user and a pet.

The dot-dash broken lines shown in FIGS. 1-2, 4, and 7-8 depict a boundary around a region of the pet carrier that forms no part of the claimed design. The dot-dot-dash broken lines shown in FIG. 9 illustrate environmental structure and form no part of the claimed design. The evenly dashed broken lines shown in FIGS. 1-5 and 7-9 depict portions of the pet carrier that form no part of the claimed design.
